Franc F. Rowell, Inventor
By his Attorney, C. Parker

UNITED STATES PATENT OFFICE.

FRANK F. ROWELL, OF BAYSIDE, NEW YORK, ASSIGNOR TO H. W. JOHNS-MANVILLE COMPANY, A CORPORATION OF NEW YORK.

HOLDING DEVICE FOR FIRE-EXTINGUISHERS.

1,222,143.

Specification of Letters Patent. Patented Apr. 10, 1917.

Application filed April 24, 1915. Serial No. 23,763.

To all whom it may concern:

Be it known that I, FRANK F. ROWELL, a citizen of the United States of America, residing at Bayside, county of Queens, State 5 of New York, have invented certain new and useful Improvements in Holding Devices for Fire-Extinguishers, of which the following is a specification.

My invention relates to hand fire extinguishers and comprises a convenient form of 10 rack or holding device for supporting such fire extinguishers or similar articles in the proper position ready for use and easy detachment from the holder.

15 The best form of apparatus at present known to me embodying my invention is illustrated in the accompanying sheet of drawings in which,

Figure 1 is a front elevation of the holder, 20 the fire extinguisher designed to be held thereby being shown in dotted lines.

Fig. 2 is a side elevation of the same parts.

Fig. 3 is a plan view of the top clip, and

25 Figs. 4, 5 and 6 are horizontal sections taken respectively on lines 4-4, 5-5 and 6-6 of Fig. 1.

Throughout the drawings like reference characters indicate like parts. 1, represents the upright member forming the backbone 30 of the apparatus which is adapted to be fastened to the wall of a building by means of screws or other convenient fastening devices passing through holes 11, 11, in the flanges of the upright, which is preferably given a 35 T-cross section, as shown in Figs. 3 to 6, with a central rib 10.

2, is a foot clip riveted to the lower end of the upright 1, as indicated at 3, 3. Preferably this foot clip is formed with two diverging channeled jaws 21, 22, each of which jaws has an inner lip 23, and an outer lip 24, so as to conveniently grasp any projecting rim B, upon the bottom of the fire extinguisher. I prefer to form this clip by 45 stamping up a single piece of metal in the shape shown in the drawings.

At the upper end of the upright there is fastened a C-shaped metal stamping 7, as by rivets 8, 8, which comprises an arch shaped 50 clip 4, designed to grasp the handle D, of the fire extinguisher A. Preferably this handle clip is recessed on its under side so that the handle D, may fit into it, as shown in Figs. 1 and 2.

55 5, is a bifurcated spring clip formed on a

lower member of the same C-shaped stamped piece and adapted to grasp the piston rod C, of the fire extinguisher and positively hold the same by spring pressure. There is also provided at the inner side of this piston rod 60 clip a downwardly extending lug 6, adapted to strike the piston lock E, on the fire extinguisher if the said fire extinguisher is presented to the holder with the lock side inward.

On the face of the upright intermediate of its length is located a socket piece 9, which has a recess in its face approximately elliptical shaped, the horizontal dimension of which is approximately equal to the diameter of the filling cap G on the fire extinguisher, while its vertical dimension is somewhat greater with the result that the projection formed by said filling cap may engage this socket piece so as to prevent lateral motion but permit slight vertical motion of the fire extinguisher. This socket piece is fastened to the upright 1, in any convenient manner, as by rivet 12.

The fire extinguisher for which my invention is primarily designed as a holder consists of a cylinder A, with piston rod C, projecting from the upper end thereof provided with a handle D and a radially projecting lug F, arranged to swing under 85 the piston lock E, when the piston rod is forced into the cylinder as far as it will go, the parts then being in the position shown in Fig. 2 in dotted lines. These extinguishers usually bear upon one side opposite to 90

that where the filling cap G, is placed, an elaborate label bearing the name of the device, that of the maker, and instructions for use. The purpose of the invention is to provide a convenient and secure holding device which will insure the operator placing his extinguisher securely in the holder and with the label side outward and the piston handle upward. To do this, the holder is first placed so that its annular base B, will 100 fit into the channel jaws 21, 22, and the same are then flexed slightly downward far enough to permit the handle D, to slip under the recess in the handle clip 4. The filling cap G, then engages the lower portion of the socket piece 9, and the piston rod C, is firmly grasped by the bifurcated spring clip 5. When the downward pressure upon the extinguisher is relieved, the foot clip bends back to its proper position, 105 110

forcing the extinguisher upward so that the handle firmly engages the handle clip 4, the filling cap G, moving into the upper position in the socket piece 9. The fire extinguisher is then firmly held against rotation and the proper exposure of the label on the outer side is insured by the fact that if a careless operator endeavors to force the extinguisher into the rack with the label side 10 inward, the piston lock E will strike the lug 6, so that it will be impossible to get the handle of the fire extinguisher into engagement with the clip 4, or the piston rod into engagement with the clip 5.

15 Having described my invention, I claim:

1. A holding device for portable fire extinguishers and the like comprising in combination a back bar of a length approximating that of the extinguisher, a foot clip 20 projecting from the lower end thereof, adapted to grasp the bottom of the extinguisher, a holder for the handle, and a bifurcated spring clip for the piston rod of the fire extinguisher extending from the upper end of the back bar, said clip being 25 provided with a projecting lug adapted to strike a projection on one side of the extinguisher, and prevent the piston rod entering the clip when the extinguisher is 30 presented to the holder with said projection on the inside.

2. A holding device for portable fire extinguishers and the like, comprising in combination a back bar, a spring foot clip projecting from the lower end of the back bar 35 and provided with upwardly extending lips

to engage recesses in the bottom of the extinguisher, a handle clip extending from the upper end of the back bar recessed on its under surface, and a socket piece on the face 40 of the back bar, adapted to engage a filling cap on the side of the extinguisher, having a recess whose vertical dimension is greater than the diameter of the cap whereby the necessary vertical motion of the extinguisher 45 to free the handle from its clips is permitted while the cap is seated in the socket piece.

3. A holding device for portable fire extinguishers and the like, comprising in combination a back bar, a spring foot clip projecting from the lower end of the back bar and provided with upwardly extending lips 50 to engage recesses in the bottom of the extinguisher, a handle clip extending from the upper end of the back bar recessed on its 55 under surface, and a socket piece on the face of the back bar, adapted to engage a filling cap on the side of the extinguisher, having a recess whose vertical dimension is greater than the diameter of the cap whereby the 60 necessary vertical motion of the extinguisher to free the handle from its clips is permitted while the cap is seated in the socket piece, together with a bifurcated spring clip adapted to engage the piston rod of the extinguisher provided with a downwardly projecting lug at its inner edge.

FRANK F. ROWELL.
